UNITED STATES PATENT OFFICE

OLAND F. BEERS, OF BELMONT, MASSACHUSETTS, ASSIGNOR TO SUBMARINE SIGNAL COMPANY, OF BOSTON, MASSACHUSETTS, A CORPORATION OF MAINE

RESONATOR

Application filed October 27, 1928. Serial No. 315,500.

The present invention relates to water resonators and in particular to such resonators mounted within a vessel or on the skin of the same.

While resonators date from the time of Helmholtz, who first explained their theory of operation and showed particularly their application to resonance in air, very little progress has been made in applying them for use in under water signaling. Attempts have been made, as shown in the Burgess et al. patents 1,301,034 and 1,301,035, to use water resonators, but apparently the resonator itself was taken for granted and no thought given to the type or kind needed for successful operation. In fact, up to the time of the present invention, it has been considered impossible to design a resonator which would be practical and useful in operation in a water medium. The general view is expressed in the German book by Franz Aigner, Unterwasserschalltechnik, page 79, the last paragraph in particular, in which the author states, after pointing out that water is 3500 times as sound hard as air:

"To this conclusion we wish to add still another important remark for practical consideration. There has not been a lack of attempts in submarine acoustics to construct water resonators similar to air resonators. The former, on account of the great water hardness, must be provided with an unusually thick wall to attain the same stiffness in the medium as compared to air. This is so difficult to attain, however, that the resonance effect will be very much poorer than in air if very special care is not taken. If, however, the great sound hardness of the water is taken into account, exceptionally heavy structures result which cannot at all be built on a ship. For these same reasons water pistles, the walls of which had to have similar protective thicknesses and weights, have no chance of success."

The relation between the thickness and diameter of a cylinder to be harder or as hard as the water is given by the author on the same page (79) as

$$\frac{d}{D} = \frac{1}{K \cdot E}$$

where K is the compressibility and E the modulus of elasticity. For steel, the author gives this as

$$\frac{d}{D} > \frac{1}{100}.$$

55

Consideration, however, will show that the relation of thickness to diameter of the value of 1/100 is really not very difficult to obtain and that under ordinary conditions this ratio will be even greater. Ordinary construction to provide walls thick enough to withstand mechanical shocks and other unexpected physical strains demands a thickness of the order of one-half inch which, with a diameter of the order of 10 inches, would make the ratio 1/20, which is 5 times as large as the minimum given by Aigner. Where investigators in the past have believed, therefore, that water resonators could not be successfully made and used because they could not be made stiff enough, I have found that the critical factor in this direction was not stiffness but something which, to all physical appearances, gave the investigators the belief that the difficulty was that of obtaining a resonator of sufficient stiffness.

The difficulty in the past has been that no potential sound energy could be stored up in the diaphragm because apparently the pressure within the resonator could not be built up on account of the expanding of the walls of the resonator, due to the lack of stiffness. I have found that the reason why the pressure could not be built up was not because of the expansion of the walls but because minute air bubbles adhered to the sides and walls of the resonator and became compressed as the pressure was built up in the resonator relieving this pressure materially, and making it appear that the resonator walls were not stiff or rigid to the forces set up.

This phenomenon was shown to be experimentally true by comparison of a resonator which was absolutely air free with one in which a given amount of air was introduced. In the latter, no appreciable pressure could be built up and the resonator not only was

far off frequency but very inefficient. Changing the amount of air in the resonator changed both the efficiency and frequency, and in fact any one condition was found hard to duplicate.

5 In the construction of the resonator I have also found that with equal and perhaps better efficiency and operation a smaller resonator was more desirable than a large one, and I have thereby been able to provide a resonator giving excellent results which can be mounted on the skin of a vessel exposed to the sound transmitting medium where formerly this was impractical on account of 10 the bulk and weight which so affected the surrounding ship's plates that the sound energy was diverted from the resonator. The weight of the resonator lowered the natural frequency of the plates so that a pressure 15 release was provided right in the vicinity of the resonator and no pressure amplitude could be built up.

Besides the features above mentioned, the construction itself provides some new features not practiced in the prior art. These 20 will be learned from the description and drawings, in which

Figure 1 shows a sectional view of one form of the invention,

30 Figure 2 shows a sectional view of a modification, and

Figure 3 shows a sectional view of a further modification.

In Figure 1, the resonator 2 is mounted on 35 the skin 1 of the vessel 1, in the same manner that a water tank used for receiving sound is mounted. In this modification the device is provided with an outer tank 4 connecting with the resonator proper by a passage or 40 orifice 14. The outer tank 4 is formed as an integral part of the whole device and is provided with a heavy flange 20 having embedded therein a rubber ring 6 which acts not only to keep the water within the tank from 45 leaking out but also as a sound insulator. The resonator 2 has in its upper part the resonator chamber 3 which is surrounded by a heavy cylindrical wall, having at its upper part a heavy flange 7 to which the back plate 50 8 is firmly fastened by bolts 15 or other suitable means. The plate 8 is provided with an opening 12 in which is inserted a diaphragm 9 carrying the microphone 10. The microphone is enclosed preferably in an air tight 55 casing 5 to protect it from physical damage. The casing 5 is provided with a cable head 13 through which the electric cable 11 passes carrying leads to the microphone 10. At the topmost part of the resonator chamber 3 is 60 provided a hole 27 which does not appear in Figure 1, since the view is a horizontal section. This is shown in Figure 3, and may also serve as a means for filling the resonator with water as well as for driving out the air 65 adhering to the sides and top of the resonator

chamber itself. The air may be driven out in any suitable way, as by rapping the sides of the chamber and the top or by boiling the water contained therein in the resonator either before or after it is filled.

In the modification shown in Figure 2, the resonator is mounted directly in the skin having its opening or orifice 14 directly to the outer water. In this modification, which is preferable in many respects to the others, the resonator is really in direct communication with the outer water, except for a thin shell or blister 25 partially shielding the space 24. The blister may be made of metal, for example, steel, or other sound transmitting material. As indicated, the wall of the blister 25 is very thin and constructed so that the sound waves are very little hindered by it. In fact, the blister 25 does not need to be water tight but can be put on in such a way that the water can enter slowly from the outer water medium. One of the chief advantages of this construction is that the water rushing by the blister when the ship is in motion does not produce a resonant note in the resonator, as is quite often the case when a fluid rushes by an orifice or opening. A similar effect would occur if one blew across the top of a bottle.

The resonator in Figure 2 is separated from the skin 1 by means of a heavy rubber insulating washer 26 which fits over the shoulder and neck of the resonator and into the opening in the vessel. In other respects the modification shown in Figure 2 is similar to that of Figure 1.

In Figure 3, the resonator is mounted in a tank 16 of the usual receiving tank type except that it is provided at one corner with a supporting member 17 to which the resonator 2 is firmly fastened. The resonator itself is similar to that of Figure 2. The sound, however, instead of entering from the outer water directly to the resonator, as is the case in Figure 2, first passes through the tank chamber and then into the resonator.

As has been mentioned before, in the topmost part of the resonator chamber a hole 27 is provided which can be plugged up by the plug 29 after the air has been driven out. In fact, the hole 27 can be omitted if the air is driven out of the resonator chamber through the orifice 14 by boiling or otherwise. This may be accomplished before installation by holding the resonator chamber in such a position that the orifice is the topmost part of the same, filling it then with water and driving the air out by shaking, rapping or boiling. After the air is out the orifice may be plugged up temporarily until the resonator is put in its position and the tank filled with water after which the plug may be removed. In Figure 3, a hole 30 is provided in the top of the tank through which the tank can be filled and in which the hand may be inserted to pull a plug which may be put in the orifice 14.

Besides taking these precautions to prevent air from remaining in the resonator, I have found also that when the resonator chamber is a casting, the casting is apt to be somewhat porous and have small cavities from which it is hard to dislodge the air. This difficulty may be overcome by coating the inside with enamel 28 or cement and thereby filling up these cavities.

In the illustration shown in Figure 1, the chamber 4 provides a means for increasing the sound pressure at the orifice 14 by coupling with the skin in such a manner that the amplitude of motion from the skin to the orifice is multiplied for the frequency of resonance. The chamber in this instance is equivalent to a so called "ton-pilz" or an elastic member comprising the elasticity of the water mass and two masses connected thereby, comprising the orifice mass and its water load and the skin mass and its water load.

The word "ton-pilz" is of German origin and is commonly understood to mean two masses connected by a substantially massless elastic member, the whole forming a vibratory system having a particular resonant frequency.

In the construction shown in Figure 1, the combination of this arrangement with the resonator is particularly useful, since it not only provides a very good tuning not too broad and not too sharp on account of the coupling, and also a very efficient receiving element, since the sound energy at the orifice of the resonator is in a very much better form to be handled, it being already concentrated in the manner in which the resonator is best able to handle it.

In my construction I am able to operate resonators efficiently and with all the practical reliability necessary for any commercial construction. I have obtained amplification twice as great or more than twice as great as the best receiving apparatus heretofore used has ever given, and in addition perhaps even more useful, have eliminated all water noise and noise of signals other than those of the desired frequency.

Having now described my invention, I claim:

1. A submarine acoustic apparatus comprising a water resonator free from air.
2. A sound receiving apparatus comprising a water resonator, a hydrophone and means for coupling mechanically and acoustically said hydrophone to said resonator, said resonator chamber being air free.
3. A sound receiving apparatus comprising a water resonator, a hydrophone and means for coupling mechanically and acoustically said hydrophone to said resonator, said resonator chamber being provided with an air vent at its topmost part to enable the air in the resonator to escape.

4. In combination, a vessel and a sound receiving apparatus mounted on the skin thereof, including an opening provided in said skin, a resonator having its orifice fitting in said opening and a thin shell enclosing said opening. 70

5. In combination, a vessel and a sound receiving apparatus mounted on the skin thereof including an opening provided in said skin, a resonator having its orifice communicating with said opening and means providing a large dead water space surrounding said opening. 75

6. In combination, a vessel and a sound receiving apparatus mounted on the skin thereof including a liquid filled resonator having an orifice and a chamber communicating with said resonator, said chamber being filled with liquid and abutting the skin of the vessel. 80

7. In combination, a vessel and a sound receiving apparatus mounted on the skin thereof including an orifice and a second chamber communicating to said resonator through said orifice, said second chamber being filled with liquid and abutting the skin of the vessel and forming a coupling means between the resonator and the skin for amplifying the amplitude of motion of the sound wave received at the skin at the resonator orifice. 85

8. In combination, a vessel and a sound receiving apparatus mounted on the skin thereof including a casing provided with two chambers, an opening connecting said chambers, a hydrophone positioned in one of said chambers, said chamber being resonant to the frequency to be received. 100

9. In combination, a vessel and a sound receiving apparatus mounted on the skin thereof including a casing provided with two chambers, an opening connecting said chambers, a hydrophone positioned in one of said chambers, said chamber being resonant to the frequency to be received and said other chamber being adapted to amplify the amplitude of motion of the sound wave received at the skin at the orifice of the resonator. 105

10. A submarine acoustic apparatus comprising sound receiving means, a resonating chamber associated therewith filled with water free from air, the system being resonant to the frequency of the sound to be received. 115

In testimony whereof I affix my signature. 120
